ATTORNEYS,

UNITED STATES PATENT OFFICE.

DUDLEY R. MORRISON, OF HARTFORD CITY, INDIANA.

CASING FOR CRUDE-OIL ENGINES.

No. 832,993.

Specification of Letters Patent.

Patented Oct. 9, 1906.

Application filed October 20, 1905. Serial No. 283,641.

To all whom it may concern:

Be it known that I, DUDLEY R. MORRISON, a citizen of the United States, residing at Hartford City, in the county of Blackford 5 and State of Indiana, have invented certain new and useful Improvements in Casings for Crude-Oil Engines, of which the following is a specification.

This invention relates to improvements in journal-bearings for explosive-engines in which the inner end of the cylinder opens into a casing within which the pitman, crank, and crank-shaft are located; and the object of the invention is to relieve the cap portion of the 15 casing, which is removable to permit access to the casing interior opposite the crank, from the full force of the explosive impulses.

The object also is to provide means adjustable from the outside of the casing for taking 20 up the wear at the main shaft-journals, thereby saving the loss of time and the annoyance incident to the removal of the casing or other parts; and a further object of the invention is to provide means for adjusting the 25 journal-boxes without danger of leakage.

I accomplish the objects of the invention by the mechanism illustrated in the accompanying drawings, in which—

Figure 1 is a detail in side elevation of that 30 part of an engine-casing which relates to my invention, showing my invention applied thereto. Fig. 2 is a vertical section on the dotted line 2 2 of Fig. 1. Fig. 3 is a detail, on a larger scale, showing the casing in side elevation with the cap partly removed and the associated parts entirely removed. Fig. 4 is a like view showing the cap in operative position on the casing, the shaft in place, and the adjustable follower and outside lower 35 removable plate assembled. Fig. 5 is a vertical section on the line 5 5 of Fig. 2, but on the same scale as Figs. 3 and 4; and Fig. 6 is a side view of the removable plate.

Like characters of reference indicate like 40 parts throughout the several views of the drawings.

7 indicates the main or body casing of the engine, which terminates on an oblique line through the axis of the main shaft, and 8 is 45 the removable extension thereof which I designate as the "cap."

9 is the main shaft of the engine, and it is mounted on journals supported by the casing. A lower portion 10 of the journal-box 50 is cast as an integral part of the casing 7.

In engines of this class the rapidly-recur-

ring explosions have a powerful tendency to open the joint between the body of the casing and the cap, and in order to resist this explosive force and tendency to open the joint 60 of the casing, which produces leakage, I provide the integral extension 11, which fits within a housing 12, cast on the cap 8. The integral parts 10 and 11 together contain one half of the bearing for shaft 9. The opposite 65 half is formed by a movable bearing-block or follower 13, which is located partly within the housing 12 and the remainder in a suitable notch 14 in the casing 7. Spacing-strips 15 are placed between the follower 13 70 and the opposite half of the journal-bearing, and as the bearing becomes worn by use one of the strips is removed, which allows the follower to be adjusted closer to the shaft. This adjustment is accomplished by means of the 75 set-screw 16, which terminates outside of the casing, where it is accessible at all times for taking up any looseness that may develop without removing the cap or opening up any of the parts. A jam-nut 17 prevents the 80 working loose of the screw.

The housing 12 extends down on the side to the plane of separation between the body 7 and the cap 8, and therefore covers the extension 11 and the upper and major portion 85 of the follower 13. A plate 19 is bolted to the outer face of the box 10 to fill out flush with the corresponding face of the housing 12. Leakage around the shaft 9 and at other joints is stopped by the packing 20, which is 90 confined by the metal ring 21. The ring 21 is split at 22, the ends being feathered and lapped, as shown in Fig. 5. Surrounding the ring and coming in to the shaft 9 with an outer face is the cap 24, which is secured by 95 bolts 25 to the housing 12 and through plate 19 to the box 10. Passing through the casing are the set-screws 27, here shown as four in number, spaced an equal distance apart and bearing at their inner ends against the 100 ring 21. As the packing 20 becomes worn the ring 21 is reduced in diameter by screwing the set-screws 27 in against it, thereby compressing the packing into the leaking joints.

The construction above described is duplicated for the journals on each side of the housing.

Having thus fully described my invention, what I claim as new, and wish to secure by 110 Letters Patent, is—

1. A casing for explosive-engines having

a separable cap united in a plane through the axis of the crank-shaft, the body portion of said casing having half bearing-boxes parts of which extend beyond said body into the cap, and an adjustable follower forming the opposite half of the journal-bearing.

2. In an explosive-engine, a body-casing and a cap joined on a plane through the axis of the crank-shaft, there being integral half journal-boxes extending from the body-casing into the cap, adjustable followers forming opposite and remaining portions of the journals, there being housings integral with the cap extending over the journal-boxes down to the plane of the joint between the body of the casing and the cap, removable plates to bring the lower parts of the boxes out flush with the housings.

3. In an explosive-engine, a body-casing and a separable cap joined on a plane through the axis of the crank-shaft, there being half-boxes integral with the body-casing, separable and adjustable half-boxes in the cap, there being housings integral with the cap within which the adjustable half-boxes are located and set-screws passing through the walls of the housings into contact with the adjustable half-boxes.

In witness whereof I have hereunto set my hand and seal, at Indianapolis, Indiana, this 6th day of October, A. D. 1905.

DUDLEY R. MORRISON. [L. S.]
